UNITED STATES PATENT OFFICE.

MIRA B. MORSE, OF INDIANAPOLIS, INDIANA.

SHOE-TONGUE FASTENER.

SPECIFICATION forming part of Letters Patent No. 728,959, dated May 26, 1903.

Application filed September 27, 1902. Serial No. 125,089. (No model.)

To all whom it may concern:

Be it known that I, MIRA B. MORSE, a citizen of the United States, residing at Indianapolis, in the county of Marion and State of Indiana, 5 have invented certain new and useful Improvements in Shoe-Tongue Supporters, of which the following is a specification.

The object of this invention is to provide an attachment for the tongues of shoes to engage the shoe-laces and hold the tongue from lateral displacement when on the foot.

The object also is to provide a neat and ornamental device which will be cheap to manufacture and of easy application to the shoe-tongue.

I accomplish the objects of the invention by the construction illustrated in the accompanying drawings, in which—

Figure 1 is a front perspective view of a 20 shoe with my invention applied; Fig. 2, a view in side elevation of the staple or fastener detached from the shoe; Fig. 3, a perspective view of the stiffening-plate used with the staple, and Fig. 4 a detail in longitudinal section of a shoe-tongue provided with my invention.

Like letters of reference indicate like parts throughout the several views of the drawings.

A represents the shoe, B the tongue, and C 30 the laces, all of usual and well-known construction.

D is a staple, preferably made of wire bent in the form shown. It is desired that the cross-bar of the staple be retained a suitable 35 distance away from the tongue to which it is fastened in order to provide a projection which, placed between the meeting edges of the split in the front of the shoe, will hold the tongue to which the staple is fastened from lateral displacement and also to provide an eyelet through which the laces of the shoe are 40 threaded in order to keep the eyelet or staple from withdrawal from the slot in the shoe-front. To retain the staple with its cross-bar thus projecting out from the tongue of the shoe, I provide the shoulders d d, formed by bending the stems of the staple inwardly and then downwardly, and these shoulders 45 gage the distance or amount of stem that can

be projected through the shoe-tongue. As 50 the substance of the tongue is soft and yielding, inasmuch as it is made out of thin leather, I reinforce it by placing a thin metal plate E over the tongue where the staple is to be applied and by passing the stems of the staple 55 through suitable perforations formed for that purpose through the plate. This plate forms a solid stop for the shoulders of the staple to rest against. The ends of the stems are carried thence through the tongue and are 60 clenched on the under side of the tongue in the manner shown in Fig. 4. The long dimension of the head of the staple is set longitudinally of the shoe-tongue, and the staple is set at the crossing of the laces, as shown 65 in Fig. 1, and may be placed at one or more points and at any desired height of the shoe.

In order to present as pleasing appearance as possible, I may ornament the outer or cross-bar of the fastener by corrugating or crimping the wire, as shown, or said bar may be engraved with a pleasing design or may be provided with an attractive jewel setting.

Having thus fully described my invention, what I claim as new, and wish to secure by 75 Letters Patent, is—

1. In a shoe-tongue holder, a staple having a cross-bar and stems bent inwardly parallel with said cross-bar to form open bends at either end of said bar and then downwardly 8, parallel but not in contact with each other to form shoulders at said last bends.

2. In a shoe-tongue holder, the combination, with a staple having a cross-bar and stems bent inwardly parallel with said cross-bar to 85 form open bends at either end of said bar, and then downwardly parallel but not in contact with each other to form shoulders at said last bends, of a stiffening and strengthening plate having perforations through which the 90 stems are inserted.

In witness whereof I have hereunto set my hand and seal at Indianapolis, Indiana, this 23d day of September, A. D. 1902.

MIRA B. MORSE. [L. S.]
